UNITED STATES PATENT OFFICE.

JAMES A. HERRICK, OF NEW YORK, N. Y.

GAS-PRODUCER.

1,100,075.

Specification of Letters Patent. Patented June 16, 1914.

Application filed February 27, 1911, Serial No. 611,033. Renewed November 12, 1913. Serial No. 800,664.

To all whom it may concern:

Be it known that I, JAMES A. HERRICK, a citizen of the United States, and residing at New York, in the county and State of New York, have invented certain new and useful Improvements in Gas-Producers, of which the following is a specification.

This invention relates to apparatus for making producer gas, and one of the objects 10 of the invention is to provide new and improved means whereby the mass within the producer will be thoroughly and continuously agitated, thereby insuring a complete consumption of the fuel, and a uniform flow 15 of gas.

Other objects will be in part obvious, and in part pointed out hereinafter.

The invention accordingly consists in the features of construction, combinations of elements and arrangement of parts, which will 20 be exemplified in the construction herein-after described, and the scope of the application of which will be indicated in the following claims.

25 In the accompanying drawings: Figure 1 is a view in vertical section, showing a preferred embodiment of my invention; Fig. 2 is a view partly in plan and partly in section of said embodiment; and Fig. 3 is a view 30 partly in elevation, and partly in section, showing a detail of construction.

Similar reference characters refer to similar parts throughout the several figures of the drawings.

35 Referring now to the drawings, the shell or casing of the producer is illustrated at 1 and is provided with an arched cover portion 2. Leading from the casing is a conduit 3, through which the producer gas is discharged, the lower end of the casing being lower at the bottom as at 4, to permit of the 40 ashes being discharged in the depression 5 formed beneath the same in the foundation of the producer. The ashes are removed 45 from this receptacle through a passage way 6, extending about the lower end of the producer. The receptacle 5 is adapted to contain the water, which forms a seal for the lower end of the producer, thereby preventing 50 a leakage of gas. Extending radially into the interior of the producer are twyer boxes 7, in the present instance three of these boxes being provided, as shown in Fig. 2 of the drawings. Each of these twyer 55 boxes is connected with a source of blast sup-

ply 8, and each box is provided with openings as at 10, through which the blast may pass into the interior of the producer. Mounted upon each twyer box, as by means of the journaled bearing 9, formed integrally theron, is a stirring device 11, each stirring device being provided with a pair of divergent legs 12 and 13, said legs being preferably set at a different angle from the vertical, as shown, one being longer than the other; such construction insuring that these legs shall pass through a different portion of the mass during the operation of the producer. Each of these stirring devices is also provided with a pair of oppositely disposed legs 14 and 15, primarily intended to prevent the formation of clinkers above the twyer boxes. These legs also aid in the agitation of the mass, and also assist in the discharge of the ashes through the lower end of the producer. Depending from the cover portion 2 of the producer, in the present instance, are three stirring members 16, each of which is provided at its upper end with a gear 17, which rests upon the cover portion, forming a support for the stirring member. These members 16 are likewise provided with divergent legs 18 and 20, set at a different angle from the vertical, one being longer than the other as in the stirring members mounted on the twyer boxes. Stirring members 11 and 16 are set in alternate relation, as shown in Fig. 2 of the drawings. The stirring members 11 mounted upon the twyer boxes 7 are each provided with a dependent hollow shaft 21, suitably journaled in the twyer boxes, the lower end of which is provided with a bevel gear wheel 22, the same meshing with a bevel gear wheel 23 carried upon a shaft 24. The opposite end of shaft 24 is provided with bevel gear 25, the same meshing with a suitably supported bevel gear 26 upon the shaft 27, the driving means of which will be hereinafter more particularly described. Each of shafts 24 which extend into the producer is protected, as by means of tube 28, one end of which is closed and the other open where it is joined with its twyer box. Apertures as at 30, are provided in the lower wall of this tube from which blast flowing into this tube from the twyer box, may be discharged into the interior of the producer.

The stirring devices 16, which depend from the cover of the producer are each

driven as by means of gear wheel 31, each of which is mounted upon one of the shafts 27; there being three of these shafts provided, one shaft for driving each pair of upper and lower stirring devices. Gear 5 wheels 31 mesh with idler gear wheels 32, suitably journaled upon the cover portion of the casing, and these idlers mesh with gear wheel 17, mounted upon the upper end 10 of the hollow shafts which carry stirring member 16. One of the shafts 27 is provided at its lower end with a bevel gear 33, which is driven as by means of a similar gear wheel 34 upon shaft 35, deriving its power from any 15 suitable source. This shaft at its upper end is provided with bevel gear wheel 36, meshing with bevel gear wheel 37 upon shaft 38, which shaft is provided at its opposite end with a bevel gear 40, which meshes with a 20 similar gear 41 provided upon the hollow shaft 42. This latter shaft extends downward through the fuel hopper 43, and its lower end carries the fuel distributing devices 44 which will not be particularly described 25 herein, inasmuch as the same form the subject-matter of my prior application, Serial No. 606,548, filed February 4, 1911, for improvements in gas producers. The remaining two shafts 27, which extend vertically 30 with respect to the producer are provided with a bevel gear wheel similar to that shown at 36, and meshes with bevel gears similar to 37 upon shafts 38, each of these shafts being provided with the gear wheels 35 40 meshing with gear wheel 41, so that when shaft 27, connected with the driving shaft 35 is rotated, the other shafts 27 will be driven thereby, being caused through the mechanism above described to rotate the 45 stirring members 11 and 16.

Uprights 45, suitably supported upon the foundation of the producer extend vertically, and extending inwardly from the upper ends of these uprights are beams 46, 50 adapted at the central portion 47 to form the bearing 48 for the shaft 42 and also to form a support for the shafts 38 and the mechanism so associated therewith.

Stirring members and associated parts are 55 water cooled in the following manner: 50 indicates a water supply pipe provided with the swiveled joint 51, from which leads pipe 52. This pipe 52 extends through hollow shaft 42 and flows into the distributing device 44, from which the water flows upward through the hollow shaft 42 and into the bowl 53, carried by shaft 42. The bottom portion of the bowl 53 is provided with small apertures 54 through which water is 60 discharged into gear 41, which gear is preferably made hollow and perforated so that the water will fill therethrough into a cup 55 surrounding the bearing 47. Leading from cup 55 are pipes 56 which lead into 65 stirring members 16, said pipes being forked

as shown so as to discharge water into the legs 18 and 20. The water discharged through the lower open end of these forked portions flows upward through the hollow shaft and is discharged upon the cover 2, 70 whence it passes through channels 60 formed upon the cover portion. Connected with these channels are pipes 61, each of which extends downwardly to the twyer boxes, and then inward toward the center of the producer to a point concentric with the axis of 75 the stirring members 11. The pipes at these points are provided with swiveled joints as at 62, from which leads a pipe 63 similarly forked to enter legs 13 and 14; the returning water flowing downward through the hollow shaft 21, the lower end of which is constricted so that the stirring member 11 is at all times full of water. This water is then discharged into the receptacle 5. 85

It will be accordingly seen that I have provided a construction well adapted, among others, to attain the aims and objects sought to be covered, in a simple yet efficient manner. By means of the peculiar construction, the mass within the producer will at all times be thoroughly agitated, and the formation of crevices therein prevented, insuring the production of gas of even quality and also insuring a steady and uninterrupted flow thereof. 90

As many changes could be made in the above construction and many apparently different embodiments of this invention could be made without departing from the scope thereof, it is intended that matter contained in the above description or shown in the accompanying drawings shall be interpreted as illustrative and not in a limiting sense. 105

It is also to be understood that the language used in the following claims is intended to cover all of the generic and specific features of the invention herein described and all statements of the scope of the invention, which as a matter of language, might be said to fall therebetween. 110

Having thus described my invention, what I claim as new and desire to secure by Letters Patent, is:

1. In producer apparatus, the combination, of a casing having a cover portion, a plurality of forked stirring members depending from the cover portion into the interior of the producer, a plurality of similarly formed stirring members suitably supported in the lower portion of the casing and extending upwardly therein, and means for driving said stirring members. 120

2. In producer apparatus, the combination, of a casing provided with a cover portion, a plurality of revolvably mounted stirring members carried thereby, a plurality of radially disposed twyer boxes in the lower portion of the casing, and a revolvably mount- 125 130

- ed stirring member carried by each of said twyer boxes, said stirring member being provided with divergent legs which extend upward into the interior of the producer and also with a plurality of horizontally disposed legs extending laterally therefrom.
3. In apparatus of the class described, the combination, of a casing provided with a cover portion and a plurality of twyer boxes, a plurality of downwardly extending revolvably mounted stirring members carried by the cover portion, and a plurality of upwardly extending revolvably mounted stirring members carried by the twyer boxes.
4. In producer apparatus, the combination with a casing, of a plurality of twyer boxes located therein, a revolvably mounted stirring member carried upon each of said twyer boxes, a shaft extending inwardly through said casing and into the twyer boxes for driving said stirring member, and a tubular member inclosing said shaft, said tubular member being provided with a plurality of blast apertures.
5. In producer apparatus, the combination, of a casing provided with a plurality of twyer boxes, a revolvably mounted stirring member carried by each of said twyer boxes, said stirring member having a shaft provided with a bevel gear, a shaft extending inwardly through the casing and into the twyer boxes having a bevel gear meshing with the first named bevel gear, means for driving said shaft, and a tubular member inclosing said shaft and forming a protective cover therefor, said tubular member being provided with a plurality of blast apertures.
6. In apparatus of the class described, the combination, of a casing provided with a cover portion and a plurality of twyer boxes, a plurality of depending revolvble stirring members carried by the cover portion, and a plurality of upwardly extending members carried by said twyer boxes.
7. In producer apparatus, the combination of a casing provided with a cover portion, a plurality of revolvably mounted stirring members carried thereby, a plurality of radially disposed twyer boxes in the lower portion of the casing, a revolvably mounted stirring member carried by each of said twyer boxes, said stirring member being provided with divergent legs which extend upward into the interior of the producer and also with a plurality of horizontally disposed legs extending laterally therefrom, and means for water cooling said stirring members.
8. In apparatus of the class described, the combination, of a casing provided with a cover portion and a plurality of twyer boxes, a plurality of depending revolvble stirring members carried by the cover portion, a plurality of upwardly extending stirring mem-
- bers carried by said twyer boxes, means for water cooling said stirring members, a receptacle formed underneath said casing, and means whereby the water from the stirring members is discharged into said receptacle.
9. In apparatus of the class described, the combination of a casing having a cover portion and a plurality of twyer boxes located in the lower portion thereof, a plurality of revolvably mounted stirring members depending from the cover portion, a plurality of upwardly extending stirring members carried by said twyer boxes, and a common means for driving said stirring members.
10. In producer apparatus, in combination, a casing, a movable stirring member extending vertically within said casing and adapted to have a field of movement therein, another movable stirring member extending vertically within said casing and adapted to have a different field of movement therein, a portion of one of said fields overlapping a portion of the other is a plurality of planes one substantially perpendicular to the other, and means for driving said stirring members.
11. In producer apparatus, in combination, a casing, a movable member extending vertically within said casing and adapted to have movement within a solid zone within said casing, another movable member extending vertically within said casing and adapted to have movement within another solid zone within said casing, one of said zones solidly intersecting the other, and means for driving said movable members.
12. In producer apparatus, in combination, a casing, a revolvble stirring member extending inwardly within said casing and having a portion offset at an oblique angle from the axis of said member, another revolvble stirring member extending inwardly within said casing and having a portion offset at an oblique angle from the axis of said member, the offset portion of one of said stirring members extending beyond the offset portion of the other of said stirring members, and means for driving said stirring members.
13. In producer apparatus, in combination, a casing, a revolvble stirring member extending in one direction within said casing and having a portion offset at an oblique angle from the axis of said member, another revolvble stirring member extending in another direction within said casing and having a portion offset at an oblique angle from the axis of said member, the offset portions of both said stirring members extending beyond each other in lengthwise relation, and means for driving said stirring members.
14. In producer apparatus, in combination, a casing, a revolvble stirring member

- extending in one direction within said casing and having a portion offset from the axis of said member, another revolute stirring member extending in an opposed 5 direction within said casing and having a portion offset from the axis of said member, said offset portions of both said stirring members extending within a common plane substantially perpendicular to the axes of 10 said members and being so disposed that a path traversed by one of said members will intersect a different path traversed by the other of said members, and means for driving said stirring members.
- 15 15. In producer apparatus, in combination, a casing having a stationary cover portion, a revolute shaft depending from the cover portion into the interior of the producer, a forked stirring member carried 20 thereby, a revolute shaft supported against translation in the lower portion of the casing and extending upwardly therein, a forked stirring member carried thereby, said members extending beyond each other 25 in lengthwise relation and being so arranged that during revolution the path traversed by a forked portion of one of said members will intersect the path traversed by a forked portion of the other of said members, and 30 means for revolving said shafts.
16. In producer apparatus, in combination, a casing, a plurality of movable stirring members having individually a substantially vertical axis of movement and 35 having in part a common field of operations but moving in different paths, a portion of one of said stirring members overlapping a portion of another at an oblique angle to the mean longitudinal axis of said

members, and means for driving said stirring members.

17. In producer apparatus, in combination, a casing, a plurality of movable stirring members having individually a substantially vertical axis of movement and 45 each carrying a plurality of terminal offset extensions, an extension carried by one of said members passing between the extensions carried by another of said members, and means for driving said stirring members.

18. In apparatus of the class described, the combination of a casing having a cover portion, a depending stirrer device extending within the interior of the casing and 50 having an upper opening, means for conducting water to said device whereby the water may flow into said device and thence through said opening, a member extending upwardly from the bottom of said casing 55 and adapted to co-act with said stirrer device, means for conducting water within said member, a conduit leading to said last-mentioned means, and a descending duct integrally formed upon said cover portion, said 60 opening letting into said duct and said duct letting into said conduit, whereby the water in passing from said opening to said conduit will in its gravity-impelled passage to said 65 upwardly-extending member flow over said cover and cool the same.

In testimony whereof I have affixed my signature in the presence of two witnesses.

JAMES A. HERICK.
